[57] CLAIM

The ornamental design for a lighter, as shown and described.

DESCRIPTION

FIG. 1 is a perspective view of a lighter showing my new design including the top, front and one side thereof;

FIG. 2 is a top plan view thereof;

FIG. 3 is a rear elevational view thereof;

FIG. 4 is a side elevational view of the side opposite that shown in FIG. 1; and

FIG. 5 is an enlarged fragmentary sectional view taken along line 5—5 of FIG. 1.

The bottom of the lighter is substantially plain and unornamented.
